(57) **CLAIM**

The ornamental design for a tool light, as shown and described.

DESCRIPTION

FIG. 1 is a perspective view of a tool light illustrating our new design in which the portions illustrated in broken lines are shown for illustrative purposes only and form no part of the claimed design;

FIG. 2 is a front prospective view, similar to FIG. 1 but on a larger scale, further illustrating the construction of the tool light;

FIG. 3 is a rear perspective view of the tool light of FIG. 2;
FIG. 4 is a side elevational view of the tool light of FIGS. 1 and 2;

FIG. 5 is a bottom plan view of the tool light of FIG. 4; and,
FIG. 6 is a top plan view of the tool light of FIG. 4.
